UNITED STATES PATENT OFFICE.

AUGUSTUS D. KLABER, OF NEW YORK, N. Y.

DESIGN FOR AN ENVELOP-BLANK.

SPECIFICATION forming part of Design No. 32,894, dated July 3, 1900.

Application filed August 4, 1899. Serial No. 726,206. Term of patent 7 years.

To all whom it may concern:

Be it known that I, AUGUSTUS D. KLABER, a subject of the Queen of Great Britain, residing in the borough of Brooklyn, city of New York, State of New York, have invented and produced a new and original Design for Envelop-Blanks, of which the following is a specification.

My invention relates to a design for envelop-blanks of the type employing a top and bottom flap and two side flaps, and the leading or material feature of my design consists in the provision of one side flap of smaller size than the other.

In order that my new and original design may be better understood, attention is directed to the accompanying drawing, forming a part of this specification, and in which is shown the envelop-blank. This blank is pro-

vided with a bottom flap 1 and a top flap 2, 20 an ordinary side flap 3, and a smaller angular side flap 4. The particular shape of the side flap 4 embodies the material or essential feature of my new and original design. This flap is angular in formation and is of smaller 25 size than the usual side flap 3.

Having now described my new and original design, what I claim, and desire to secure by Letters Patent, is—

The design for an envelop-blank herein 30 shown and described.

This specification signed and witnessed this 27th day of May, 1899.

AUGUSTUS D. KLABER.
